UNITED STATES PATENT OFFICE.

LEWIS T. WILCOX, OF PEEKSKILL, NEW YORK.

LIQUID-FUEL BURNER.

Application filed May 19, 1925. Serial No. 31,285.

As heretofore constructed liquid fuel burners of the type to which my invention relates have been so made as to include a casing, a wick holder movable within the casing, 5 to adjust a wick carried thereby to position, and devices for shifting the position of the wick holder to correspondingly determine the position of the wick for use. Ordinarily, these wick holders have been provided with 10 a plurality of apertures and corresponding intervening portions, and a pinion has been employed for engagement with this portion of the wick holder to effect the movement thereof. However, so far as I 15 am aware it has been customary heretofore to apply the pinion or similar device to one portion only of the wick holder, whereby as will be appreciated there was a tendency to cause the wick holder to bind or wedge 20 in the casing, and also to cause the outer portion of the wick to extend unevenly beyond the peripheral edge of the casing, resulting in an uneven flame in the use of the burner.

25 The object of my present invention is to overcome these disadvantages by the provision of actuating devices for the wick holder in the use of which the wick holder is simultaneously engaged at oppositely disposed portions thereof, whereby in adjusting the wick holder and its wick to position a uniform movement is imparted to the wick holder, and in adjusting the wick all the parts thereof project evenly beyond the 30 peripheral portions of the casing, resulting 25 in a frame of uniform height in the use of the burner.

To this end in carrying out the invention the wick holder is preferably provided in 40 oppositely disposed portions thereof, with a plurality of apertures and intervening parts acting as racks to be engaged by suitable pinions, or otherwise, operated simultaneously through sets of gears and the necessary shafts for operating the same, these parts being exterior of the burner casing as will be hereinafter more particularly 45 described.

In the drawing Fig. 1 is an elevation and 50 partial cross-section of a liquid fuel burner made in accordance with my invention.

Fig. 2 is a partial plan and section of the same.

Fig. 3 is a sectional elevation illustrating the relationship between the wick holder and 55 the pinions for operating the same, as employed on one side of the casing.

Fig. 4 is an elevation of the wick holder and wick carried thereby.

Fig. 5 is a sectional plan illustrating 60 another form of the invention.

Fig. 6 is a partial elevation of the form of the burner as shown in Fig. 5.

Referring to the drawings, and particularly to Figs. 1 to 4, inclusive, in which I 65 have illustrated one embodiment of the invention it will be seen that in carrying out the same the liquid fuel burner comprises a casing having a cylindrical wall 10, adapted to receive and contain a wick holder 11. 70 These members as will be understood may be made from suitable sheet metal or other similar material in the customary manner. In oppositely disposed positions as indicated at 12, and 13, the wick holder 11 is 75 provided with a plurality of apertures which with the intermediate portions of the wick holder are adapted to function as racks, as will be hereinafter more particularly described. It will also be understood that 80 the wick holder 11 is adapted in a suitable manner to receive and carry a wick 14.

In a suitable position, that is, at a pre-determined elevation, the wall 10 is fitted with a housing 15. Within this housing 15 85 there is an end bearing or socket 16 adapted to receive the inner end of a shaft 18, upon which pinions 19 and 20 are mounted and maintained in a spaced relationship by a collar or spacer 21, or otherwise. The shaft 90 18 also passes through and is journaled in a bearing 17, suitably fixed in the opposite wall of the housing 15. As illustrated, the bearing tube 17 terminates at its outer end in an enlarged exteriorly screw threaded 95 head adapted to receive a packing nut 22, for the employment of a packing ring 23, to make a tight joint with the shaft 18.

The shaft 18 also passes into a gear casing 24, being journaled in bearings 25 connected 100 to the gear casing. Within the gear casing 24 the shaft 18 is provided with a worm gear

26 adapted to mesh with a worm 27 also within the gear case 24, and secured to a shaft 28. This shaft 28 also passes through the gear case and is journaled in suitable bearings 5 connected thereto.

The apparatus includes a second gear case 30, similar in all respects to the gear case 24. The shaft 28 passes through this second gear case 30 and is journaled in bearings 31 carried thereby. At this end of the shaft 28 the same is provided with a hand wheel 32, by which, as will be understood the shaft may be turned in either direction. Within the gear case 30 the shaft 28 is fitted with a worm 33. This worm 33 meshes with a worm gear 33' mounted within the gear case 30 on a shaft 34, which corresponds to the shaft 18. The shaft 34 is journaled in bearings 35, connected with the gear casing 30, and is fitted with a packing nut 36, adapted to contain a suitable packing ring and to be turned down on the screw threaded head of a bearing sleeve 37, corresponding with the bearing sleeve 17. The shaft 34 passes into a housing 38 where it is provided with pinions 39 and 40, corresponding with the pinions 19 and 20, respectively. The teeth of the pinions 39 and 40 are adapted to enter the apertures provided in the apertured portion 12 of the wick holder, and in a similar manner the teeth of the pinions 19 and 20 are adapted to enter the apertures of the apertured portion 13 of the wick holder.

35 It will now be understood that by turning the shaft 28, which may be considered a drive shaft in either direction, the shafts 34 and 18, which may be considered counter-shafts may be turned in opposite directions 40 by arranging the worms and worm gears to so turn these shafts, and thereby impart the necessary movement to the sets of pinions 39 and 40, and 19 and 20, to impart simultaneously to opposite sides of the wick holder a uniform movement, thereby preventing the wick holder from becoming wedged and effecting a uniform height of the wick and a correspondingly uniform height of the flame is produced thereby in use.

50 By reference to Figs. 5 and 6, it will be seen that instead of employing the worm wheels and worm gears the same object may be accomplished by the use of spur gears. To this end the wall 10 in a suitable position is provided with a housing 41, extending into which there is a shaft 42. Mounted on this shaft 42 are pinions 43 and 44, adapted to engage the wick holder at one side thereof. The shaft 42 passes through 55 a sleeve bearing 45 and is fitted with a packing nut 46 for making a tight joint with the shaft. The shaft 42 also passes into a gear casing 47, the shaft being journaled in suitable bearings 47' connected to the gear case. Within the gear case 47 the shaft 42

carries a spur gear 48. This spur gear meshes with a similar gear 49 carried by a shaft 50. The shaft 50 also extends into the gear case and is journaled in a suitable bearing 51 connected thereto. The shaft 50 70 passes through a gear case 52, and is journaled in bearings 53 connected thereto. At the free end of the shaft 42 the same is fitted with a hand wheel 54, by which the shaft may be turned in either direction. 75 Mounted on the shaft 50 within the gear case 52 is a spur gear 55. This spur gear 55 meshes with a similar gear 56 mounted on a shaft 57, passing into the gear case 52 and journaled in bearings 58 connected thereto. On the shaft 57 there is a packing nut 57', and the shaft 57 passes through and is journaled in a bearing sleeve 59 connected to the housing 60, secured to the wall 10 in a position oppositely disposed to the 80 housing 41. Within the housing 60, the shaft 57 is fitted with spaced pinions 62 and 63, extending through an aperture in the wall 10 at this side thereof, so as to engage the apertured or rack portion 12 of the wick 85 holder on this side thereof. The parts of the apparatus in this construction as will be obvious, operate in a manner similar to those hereinbefore described, and are adapted to simultaneously effect a uniform movement of the wick holder from oppositely disposed sides thereof to prevent the same from wedging, and to cause the wick to evenly project in all portions thereof beyond the peripheral edge of the wall 10, to obtain a uniform height in the flame from 90 the wick when the burner is in use.

I claim as my invention:

1. In a liquid fuel burner, a casing, a wick holder having oppositely disposed rack 105 portions, housings extending in oppositely disposed positions from the said casing, shafts mounted in the said housings, means carried by the shafts for engaging the racks of the wick holder, and means for turning 110 the said shafts to raise and lower the wick holder simultaneously from opposite sides thereof.

2. In a liquid fuel burner, a casing, a wick holder having oppositely disposed 115 racks therein, housings extending in oppositely disposed positions from the said casing, a bearing mounted in each of the said housings, a shaft journaled in each of said bearings, pinions carried by the said shafts 120 and adapted to engage the racks of the wick holder, and means for turning the said shafts to raise and lower the wick holder.

3. In a liquid fuel burner, a casing, a wick holder having oppositely disposed racks 125 therein, a housing extending from the said casing, a bearing mounted in the housing, a shaft journaled in the bearing, pinions mounted on the shaft and adapted to engage one of the said racks in the wick holder, a 130

second housing extending in an oppositely disposed position from the said casing, a bearing in the said second housing, a shaft journaled in the said second bearing, pins mounted on the said second shaft and adapted to engage another rack in the wick holder, the said shafts extending from the

said housing in substantially parallel positions, and means for simultaneously operating the said shafts to raise and lower the 10 said wick holder.

Signed by me this 15th day of May, 1925.

LEWIS T. WILCOX.
